SAFETY RAZOR

Barney R. Nyhagen, New York, N. Y.

Application August 19, 1949, Serial No. 111,193

2 Claims. (Cl. 30—60)

1

This invention relates to a safety razor which is constructed and arranged to permit of limited flexing of the blade intermediate the ends thereof.

The invention comprehends a safety razor including a flexible blade and a blade holder having clamping means for holding the blade against movement at the ends thereof but which permits of limited flexing of the blade toward and away from the guard edge thereof intermediate the ends of the blade.

Another object of the invention is to provide a blade holder having blade clamping elements which are movable into engagement over the ends of the blade for releasably securing the blade on the holder and which includes a clamping element adapted to be moved into overlying relation with the blade substantially centrally thereof for limiting the outward flexing of the blade.

Still another object of the invention is to provide a razor blade including a holder having a guard edge disposed in spaced relation from the cutting edge of the blade and with clamping means for releasably securing the blade in position thereon to permit of limited flexing of the cutting edge portion of the blade toward and away from the guard edge.

With the foregoing and other objects in view, reference is now made to the following specification and accompanying drawings in which the preferred embodiments of the invention are illustrated.

In the drawings:

Fig. 1 is a side view of a razor constructed in accordance with the invention and illustrating the handle partly broken away to disclose the underlying structure.

Fig. 2 is a top plan view thereof showing the blade in broken line.

Fig. 3 is an enlarged longitudinal vertical sectional view taken approximately on line 3—3 of Fig. 2 with the handle broken away.

Fig. 4 is an enlarged transverse sectional view taken approximately on line 4—4 of Fig. 2.

Fig. 5 is a side view of a razor constructed in accordance with the invention showing the handle partly broken away and illustrating a modified form thereof.

Fig. 6 is a top plan view thereof.

Fig. 7 is an enlarged vertical sectional view taken approximately on line 7—7 of Fig. 6.

Fig. 8 is an end elevation thereof with parts broken away.

Fig. 9 is an enlarged top plan view of the razor

2

shown in Fig. 5 with the blades removed and the blade clamping elements in upstanding position.

Fig. 10 is an end view thereof with parts broken away.

5 Referring to the drawings by characters of reference and more particularly to the form of the invention illustrated in Figs. 1 to 4 inclusive thereof, the razor includes a blade holder 10 having one or more longitudinally extending 10 guard edges 11, two being shown in the embodiment illustrated for accommodating a double-edge blade B having oppositely disposed longitudinally extending cutting edges 12. The blade is formed with a longitudinally extending 15 slot 13 located centrally between the cutting edges and is provided with notches 14 at the corners thereof.

The blade holder 10 is formed with a rectangular recess 15 extending longitudinally between 20 the longitudinal edge portions 16 thereof in which is fitted a plate 17 secured thereto by rivets 18 at the opposite ends and having depending transversely extending flanges 20 at its ends which provide a transversely extending recess 21 in 25 the under side of said plate between the flanges and between the plate 17 and the bottom of the recess 15. The plate 17 is formed with raised corner portions 22 while the longitudinal edge portions 16 of the holder are formed with raised 30 ends 23 which raised corner portions and ends constitute supporting surfaces at the corners of the holder for supporting the blade B in position thereon with the upper surfaces of the longitudinally extending edge portions 16 between the raised ends 23 being located in spaced relation below the cutting edges 12 of the blade and extending outwardly beyond the said cutting edges.

The holder 10 is rigidly affixed to a tubular 40 handle 24 in which a shaft 25 is mounted for swivel turning movement with the lower end thereof secured to a manipulating knob 26 and the upper end of the shaft secured to a cam disk 27 located in a circular recess 28 formed in the 45 holder and opening into the recess 21 between the holder and the plate 17. Arranged in the recess 21 for guided longitudinal reciprocatory movement are oppositely disposed rectangular plates 30 and 31 which slidably fit therein between the 50 opposite side walls of the recess 15 and are formed with outwardly directed terminals 32 at the outer ends thereof which protrude through recesses 33 in the raised corner portions 22 and have inwardly directed free upper ends 34 55 adapted to be moved into overlying relation with

the notched corners of the blade for securing the blade in position upon the raised corner portions 22 and the raised ends 23 of the longitudinally extending edge portions 16.

In order to impart longitudinal reciprocatory movement to the plates 30 and 31 for moving the free ends 34 of the terminals 32 into and out of overlying relation with the blade, the cam disk 27 is formed with oppositely disposed arcuate slots 35 opening through the upper face thereof which are engaged by pins 36 depending from the plates 30 and 31. The arcuate slots 35 are formed eccentric to the axis of the shaft 25 whereby turning of the shaft by manipulating the knob 26 will rotate the cam disk 27 to produce a camming action of the edges of the slots against the pins 36 to thereby move the plates 30 and 31 outwardly when the knob 26 is turned in one direction so as to move the free upper ends 34 of the terminals 32 out of overlying engagement with the blade and when the knob 26 is turned in the opposite direction to thereby move the plates 30 and 31 inwardly so as to move the ends 34 of the terminals 32 into overlying clamping engagement with the blade.

In order to limit the outward flexing of the blade B without interfering with the inward flexing thereof towards the longitudinal edge portions 16 intermediate the ends of the blade, the cam disk 27 is formed with a central stud 37 which protrudes outwardly through a central opening 38 in the plate 17 and is provided with an elongated head 39 which is rotatable from an aligned position with the slot 13 in the blade to a transversely extending position in overlying relation with the blade to thereby dispose the outer ends of the head 39 adjacent the cutting edges thereof. It will be understood that when the head 39 is in the aligned position with the slot 13 in the blade, the free ends 34 of the terminals 32 will be moved outwardly from overlying relation with the blade so that the blade can be removed from the holder and when the head 39 is moved to a position transversely of the blade, the free ends 34 of the terminals 32 are moved inwardly into overlying relation with the blade for securing the blade on the holder.

The blade holder 10 is provided with a rib 41 extending longitudinally of and projecting upwardly from the upper surface of the plate 17 and which is cut away centrally thereof to receive the elongated head 39 in alignment with the end portions of the rib and which end portions of the rib project through the slot 13 in the plate for positioning the blade upon the blade holder.

In order to tension the shaft 25 against too free turning movement a spring washer 42 is located in a recess 43 at the lower end of the handle 24 which frictionally engages the inner end of the knob 26.

In the form of the invention illustrated in Figs. 5 to 10 inclusive of the drawings, the razor includes a blade holder 45 having one or more longitudinally extending guard edges 46, two being shown in the embodiment illustrated for accommodating a double-edge blade C similar to the blade B in the previous form of the invention and having oppositely disposed longitudinally extending cutting edges 47. The blade holder 45 is formed with raised ends 48 at the opposite ends of the longitudinally extending edge portions 49 located on opposite sides of the holder for supporting the blade in position on said raised ends 48 with the longitudinally extending edge portions 49 between the raised ends 48 being lo-

cated in spaced relation below the cutting edges 47 of the blade and with the longitudinally extending edge portions 49 extending outwardly beyond the cutting edges thereof.

The blade holder 45 is rigidly affixed to a tubular handle 50 in which a shaft 51 is mounted for swivel turning movement with the lower end of the shaft 51 secured to a manipulating knob 52 and the upper end of the shaft extending into an annular recess 53 in the holder 45. The shaft 51 is formed with an interiorly threaded opening 54 in the upper end thereof in which is threadedly received a threaded shank 55 depending from the lower edge of a vertically disposed bar 56 extending longitudinally of the holder and which is of a length to engage through the longitudinally extending slot 57 in the blade C for disposing the blade in position on the holder.

By turning the manipulating knob 52 the bar 56 is movable from a retracted position in which the lower portion thereof is disposed in a longitudinally extending slot 59 in the holder with the upper portion thereof projecting therethrough to a projected position in which the bar is disposed above the holder. Arranged on the holder for movement with the bar 56 are oppositely disposed clamping elements 60 which are swingable from an overlying clamping relation with the blade to an upstanding released position in which the blade may be removed from the holder.

The clamping elements 60 each include a flat inner portion 61 and right angularly related ends 62 which extend laterally outward therefrom and are formed with depending projections 63 having inwardly offset lugs 64 at the inner ends thereof. The said projections have reciprocatory movement in notches 65 at the corners of the holder with their lower ends pivoted on pivot pins 66 to arms 67 extending outwardly from the ends of the bar 56. The holder is formed with inclined walls 68 on one side of the notches 65 which are engaged by the lugs 64 for imparting turning movement to the clamping elements 60 to thereby swing the same into overlying clamping relation with the blade when the manipulating knob 52 is turned in one direction and to cam the lower end of the projections 63 inwardly so as to swing the clamping elements on the pivot pins 66 into an upstanding released position when the manipulating knob is turned in the opposite direction to elevate the clamping elements 60.

The clamping elements 60 are also formed with medial tongues 69 extending laterally outward from the inner portion 61 thereof centrally between the ends 62 with the free ends of the tongues adapted to be disposed adjacent the cutting edges of the blade when the clamping elements are arranged in overlying clamping relation with the blade. The tongues 69 function to limit the outward flexing of the blade intermediate the ends thereof but permit flexing thereof between the longitudinally extending edge portions 49 while the ends 62 of the clamping elements engage against the blade at the ends thereof and clamp the same against the raised ends 48.

What is claimed is:

1. In a safety razor, a blade holder having guard edge portions at the opposite sides thereof and raised areas at the opposite ends of said guard edge portions for supporting the blade at the four corners thereof with the blade disposed flatly upon said raised areas with the cutting edges thereof spaced above the guard edge portions be-

tween said raised areas, blade clamping means movable into overlying relation with the blade at the ends thereof for releasably securing the blade in flat unflexed condition on the holder, a medial clamping element movable with said means into overlying relation with the blade medially of the ends thereof for preventing the outward flexing of the blade and permitting of the inward flexing of said blade between said raised areas, a handle, and a manipulating knob carried by said handle for manually moving said blade clamping means and said clamping element into and out of overlying engagement with the blade.

2. In a safety razor, a blade holder having a top wall provided with raised portions at the corners thereof with the upper surfaces of said raised portions being disposed in alignment for supporting the blade at the corners thereof in flat elevated relation above the intermediate edge portions of the top wall, clamping means mov-

10

20

able into overlying relation with the blade above said raised portions and medially of the ends thereof for releasably securing the blade on said top wall and for preventing the outward flexing of the blade between said raised portions and permitting of the inward flexing of said blade due to the flat unflexed condition thereof.
